LENS MARKING GAUGE

Carl W. Focht, South Williamsport, Pa., assignor
of one-half to The Valley National Bank of
Phoenix, Phoenix, Ariz., a National Banking
Association

Application May 10, 1945, Serial No. 593,001

2 Claims. (Cl. 33—174)

1

This invention relates to marking gauges for ophthalmic lenses which, in the further discussion, will be referred to as "lenses," but the character of the invention will be considered in connection with the aforesaid definition.

It is an object of the invention to produce a marking gauge whereby the locations of holes for receiving the fastenings of mountings for such lenses may be accurately determined expeditiously, and furthermore to provide novel means associated with a lens support for holding the lens in certain relation to gauges or abutments whereon the lens is held while being marked.

It is furthermore an object of the invention to provide a base and adjustable elements mounted thereon which may be manipulated for registering positions where the lens is to be drilled for the mountings thereof.

A further object of the invention is to provide a member for engaging a portion of the periphery or edge of the lens, in association with resilient means for exerting pressure on said embracing member and on other parts which may be brought into play for exerting pressure on the lens in a direction at an angle to the peripheral engaging means.

It is a still further object of the invention to provide a base for supporting the lens, and members which are adjustable diagonally of the base, which members have graduations and numerals on their surfaces near the lens-engaging edges thereof, the said members and base being provided with guiding means for causing the cooperation of the said members with a lens interposed between them; and it is furthermore the purpose of the inventor to provide means for retaining one member stationary while the other is being manipulated with relation to the edge of the lens to bring them into coordination for a reading of the graduations with respect to a marking on the lens, which is commonly referred to in the art as the "grinding" line.

A further object of the invention is to provide a device of this character in which the lens and members carrying the graduations may be expeditiously manipulated for arriving at the locations where holes are to be bored in the lens for the mountings.

With the foregoing and other objects in view, the invention consists in the details of construction, and in the arrangement and combination of parts to be hereinafter more fully set forth and claimed.

In describing the invention in detail, reference will be had to the accompanying drawings for-

2

ing part of this application, wherein like characters denote corresponding parts in the several views, and in which—

Figure 1 illustrates a plan view of the base, showing a lens engaged by the elements of the combination for retaining it in place;

Figure 2 illustrates a view in elevation of the under side of the lens supporting member and parts associated therewith;

Figure 3 illustrates a sectional view of the assembly on the line 3—3 of Fig. 1;

Figure 4 illustrates a sectional view on the line 4—4 of Fig. 1;

Figure 5 illustrates a sectional view on the line 5—5 of Fig. 1;

Figure 6 illustrates a sectional view on the line 6—6 of Fig. 1; and

Figure 7 illustrates a perspective view of one of the graduated lens-engaging members.

In these drawings 10 denotes a base or table which is provided with radial slots 11 and 12, in which guiding pins 13 and 14 are slidable, the said guiding pins each depending from sliding blocks 15 and 16, respectively, and each guiding block has an aperture such as 17. The purpose of the aperture in each block is that they may be selectively occupied by a peg 18 which enters an aperture 19 in the base or table. The peg is removable and may be used in connection with either sliding block while the other one is left free for movement longitudinally and somewhat transversely of the table as the block is guided in the appropriate slot. The guiding pins 13 and 14 which depend from the sliding blocks 15 and 16 have blocks 15a and 16a respectively, attached at their lower ends below the base 10, and a coiled spring 20 has its ends 21 connected to the said blocks 15a and 16a, and the said spring embraces a wheel or pulley 22 rotatably mounted on a stud 23, which stud is anchored in the table on its underside and it will thus be seen that when one of the blocks is held stationary by a peg, the other block may be manipulated, as will presently appear, to position the grinding line of the lens parallel with a line extending from the graduation 50 on the stationary block. It is shown that the graduations of conventional type are numbered 38, 40, 42, 44, 46, 48 and 50.

A flexible band 24, preferably of metal, has one end anchored to each sliding block, as shown at 25, and this band is of such length that it engages the edge or periphery of the lens and it aids in the retention of the lens as it is frictionally held in position by the tension on the sliding

blocks occasioned by the function of the spring 20.

In operating the lens marker, it is suggested that the entire device thus described be held between the two hands of an operator and that pressure be exerted on the thumb piece at the bottom of the block that is free to slide and that it be pushed upwardly toward the right hand corner. The lens should then be inserted preferably by using the left thumb to manipulate the lens and the lens should be so positioned with its convex side up, in order that it may be engaged by the block when the block is released against the edge of the lens. The lens should then be adjusted with the grinding line thereof in a line parallel with the extension of the line 50 extending from the left block. Line 50 is the location for the mounting on the nasal side of the lens and it is immaterial whether the grinding line on the lens is exactly over the line 50 from the left, but it must be adjusted so that it is parallel with the line 50 from the left, whether above or below or exactly over it. For odd shaped lenses, it might be necessary to hold the lens up in position by pushing upwardly on the bottom of the lens with the left thumb so that the metal band around the top of the lens is tight against the lens. The first step is to mark the location of the hole on the nasal side of the lens which is always placed on the lens at line 50 from the left marking block, as it is illustrated in Figure 1. The mark for the hole on the opposite edge of the lens is located by determining the size of the lens and marking it at a graduation which corresponds with the number or size of the lens as, for example, if a size 42 lens is used, the mark for the hole on the right side, which would be the outside edge of the lens, would be on the line 42 on the right hand marking block. If the grinding line on the lens is kept parallel with the extension of the line 50 on the left block and the lens is held firmly up in place by pushing on the bottom of it, the accurate location of the outside hole for grinding can be easily and quickly ascertained by using the graduations or marking lines on the right sliding block.

The foregoing operation is followed for marking the left lens. The right lens can be marked by placing the left lens over the right lens and marking through the holes. However, if only the right lens is to be drilled, the lens could be marked with the same device by merely taking the peg out of the left sliding block and pushing the right sliding block upwardly toward the right hand corner until the peg can be inserted in the holes along the line 50 on the right, and thereafter the

operation would be the same as has been explained, except that the left marking block would be manipulated and the graduations would be made from the left marking block.

5 The base may have a support 26 at its rear edge and a support 27 at its front edge, the former of which is higher than the support 27 in order that the base may be supported at an inclined position, as such position better adapts the mechanism for convenient reading and manipulation.

10 I claim:

1. In a lens marking gauge, a base, blocks movably mounted thereon having approximately parallel edges and graduations on their surfaces near the said edges, means for guiding the blocks divergently during their movement toward the upper edge of the base, means for selectively holding either of the blocks in a predetermined position while the other is movable with relation to it, a flexible band having a looped portion between the said blocks and having its ends connected to said blocks whereby the band may partially embrace the edges of a lens interposed between the blocks, and means for exerting a pull on the blocks 15 against the action of pressure tending to move the blocks toward the upper edge of the base.

2. In a lens marking gauge, a base, blocks movably mounted thereon having approximately parallel edges and graduations on their surfaces near the said edges, means for guiding the blocks divergently during their movement toward the upper edge of the base, means for selectively holding either of the blocks in a predetermined position while the other is movable with relation to it, a flexible band having a looped portion between the said blocks and having its ends connected to said blocks whereby the band may partially embrace the edges of a lens interposed between the blocks, and means for exerting a pull on the blocks 20 against the action of pressure tending to move the blocks toward the upper edge of the base.

3. In a lens marking gauge, a base, blocks movably mounted thereon having approximately parallel edges and graduations on their surfaces near the said edges, means for guiding the blocks divergently during their movement toward the upper edge of the base, means for selectively holding either of the blocks in a predetermined position while the other is movable with relation to it, a flexible band having a looped portion between the said blocks and having its ends connected to said blocks whereby the band may partially embrace the edges of a lens interposed between the blocks, and means for exerting a pull on the blocks 25 against the action of pressure tending to move the blocks toward the upper edge of the base.

4. In a lens marking gauge, a base, blocks movably mounted thereon having approximately parallel edges and graduations on their surfaces near the said edges, means for guiding the blocks divergently during their movement toward the upper edge of the base, means for selectively holding either of the blocks in a predetermined position while the other is movable with relation to it, a flexible band having a looped portion between the said blocks and having its ends connected to said blocks whereby the band may partially embrace the edges of a lens interposed between the blocks, and means for exerting a pull on the blocks 30 against the action of pressure tending to move the blocks toward the upper edge of the base.

5. In a lens marking gauge, a base, blocks movably mounted thereon having approximately parallel edges and graduations on their surfaces near the said edges, means for guiding the blocks divergently during their movement toward the upper edge of the base, means for selectively holding either of the blocks in a predetermined position while the other is movable with relation to it, a flexible band having a looped portion between the said blocks and having its ends connected to said blocks whereby the band may partially embrace the edges of a lens interposed between the blocks, and means for exerting a pull on the blocks 35 against the action of pressure tending to move the blocks toward the upper edge of the base.

6. In a lens marking gauge, a base, blocks movably mounted thereon having approximately parallel edges and graduations on their surfaces near the said edges, means for guiding the blocks divergently during their movement toward the upper edge of the base, means for selectively holding either of the blocks in a predetermined position while the other is movable with relation to it, a flexible band having a looped portion between the said blocks and having its ends connected to said blocks whereby the band may partially embrace the edges of a lens interposed between the blocks, and means for exerting a pull on the blocks 40 against the action of pressure tending to move the blocks toward the upper edge of the base, said means comprising a resilient element having its ends immediately connected to the blocks, and an element stationed between and below the blocks 45 around which the flexible element operates.
